UNITED STATES PATENT OFFICE.

HOWARD L. WOOD, OF COLUMBUS, OHIO, ASSIGNOR TO THE RAIL JOINT COMPANY, OF NEW YORK, N. Y., A CORPORATION OF NEW YORK.

INSULATED RAIL-JOINT.

1,087,623.

Specification of Letters Patent.

Patented Feb. 17, 1914.

Application filed October 12, 1912. Serial No. 725,457.

To all whom it may concern:

Be it known that I, HOWARD L. WOOD, a citizen of the United States, residing at Columbus, in the county of Franklin and State of Ohio, have invented certain new and useful Improvements in Insulated Rail-Joints, of which the following is a specification.

This invention relates to the subject of rail joints, and more particularly to the construction of a splice bar or joint bar which possesses special utility in its application to a rail joint of the insulated type, though embodying characteristics which render the same useful in standard joint constructions.

To this end the invention contemplates a novel and practical construction of insulated rail joint, and also a novel and practical design of splice bar embodied therein, the improved construction being intended to secure the solidity and base-supporting strength of a standard joint, while at the same time thoroughly insulating the joint throughout with the use of a minimum amount of insulating material.

In carrying out the foregoing general objects, the invention has in view a construction wherein each joint bar provides a rail-supporting base throughout the entire length of the joint and also provides a direct metallic bearing with the under side of the head and the upper side of the rail base flange for one rail end, while the other rail end, at the same side of the joint, is adapted, with the improved splice bar, to be combined with a wooden or equivalent filler member. This secures, in connection with a single splice bar, the combined advantages of the standard joint bar having a rail supporting base plate, and a construction employing a

wooden or equivalent filler member. Furthermore, this novel combination admits of a simple and practical arrangement of parts whereby the filler elements may be utilized as a part of the joint insulation so that it is only necessary to employ a small amount of insulating material, respectively at the base of the rails and between the rail ends, in order to secure a complete insulation of the joint without detracting in the slightest from its effectiveness as an insulated joint.

Though susceptible of embodiment in different forms of construction without departing from the spirit or scope of the invention, the same consists in the novel construction, combination and arrangement of parts here-

in after more fully described, illustrated, and claimed, and for purposes of illustration, one simple and practical form of construction for carrying the invention into effect is shown in the accompanying drawings, in which—

Figure 1 is a sectional perspective view of a rail joint of the insulated type embodying the improvements claimed herein; Fig. 2 is a top plan view of the same; Fig. 3 is a cross sectional view of the joint on the line 3—3 of Fig. 2, showing the cross sectional form of the joint at the end opposite that shown in Fig. 1; Fig. 4 is a detail perspective view of the novel form of splice bar.

Like references designate corresponding parts in the several figures of the drawings.

Referring to the illustrated embodiment of the invention shown in the drawings, the numerals 1 and 2 designate the respective rail ends of the joint, and, according to the present invention, it is proposed to associate therewith at each side of the joint, a novel form of splice bar or joint bar. This bar, as plainly illustrated in Fig. 4 of the drawings, is not of uniform design throughout. Each half thereof is of a different design from the other half, and in part, subserves different functions, though both halves are integrated and are provided with rail supporting base plates so that the rails have a base support throughout the entire length of the joint. The bar as a unit is designated by the reference numeral 3 and the same consists of what may be termed a fishing-space member 4 and a shoe-angle member 5, each of which members is of a length approximately equaling one-half the length of the joint.

The fishing-space member 4 of the splice bar 3 includes an upright member 5^a provided at its upper edge with a bearing head 6 for engagement beneath the head of the rail and having formed therewith, at its lower edge, the inclined outwardly extending foot flange 7 which overlies and directly bears upon the upper side of the rail base flange of a rail. This foot flange 7 of the fishing-space member has formed integrally therewith the horizontal inwardly extending base plate 8 which underlies, and constitutes the supporting base for, a rail, there being a rail flange receiving groove or channel 9 provided between the foot flange 7 and the base plate 8.

The shoe-angle member 5 of each splice bar 3 forms the other half of the latter and is integrally or otherwise rigidly united with the fishing-space member 4 by means of a 5 connecting web or equivalent union 10 between the upper portion of both members of the bar. In structure, the said shoe-angle member 5 consists of the right angularly related parts 11 and 12, the part 11 constituting an upright clamping or bolt plate, and the part 12 constituting a rail supporting base plate which underlies and supports the rail. A continuous foot flange extension 13 may be provided along the outer lower edge 15 of the combination splice bar throughout the entire length thereof if desired or preferred, said foot flange extension being utilized for reinforcing or other purposes.

In the application of the improved combination splice bar to a rail joint, the same possesses special utility in a joint of the insulated type, such as shown in the accompanying drawings. Referred to this use of the improved bar it will be observed that one 20 of the same is arranged at each side of the joint. As thus arranged, the fishing-space member 4 of each bar closely fits in the fishing-space of one rail end so as to have a direct metallic bearing engagement with the 25 under side of the rail head and the upper side of the rail base flange, with the base plate 8 disposed beneath and supporting the rail bottom. The other member 5 of the same bar receives the other rail end, but by 30 reason of the offsetting of the upright clamping plate 11, the latter is offset from said other rail end and is adapted to be combined with a wooden or equivalent filler member 14. This filler member is interposed 35 between the upright clamping plate of the shoe angle and the adjacent rail side, fitting in the fishing space of such rail and having a direct bearing engagement at 14^a with the under side of the rail head, and a direct 40 bearing engagement as at 15 with the upper side of the rail base flange, thus contributing materially to the solidity of the joint and the 45 support of the rails, while also performing an insulating function.

50 In the preferable application of the invention, shown in the drawings, it may be observed that the opposite splice bars are arranged in reverse relation with the fishing-space member of one bar fitting one rail end 55 and the fishing-space member of the other bar fitting the other rail end, and the shoe angle members 5 of the separate bars correspondingly related, thus disposing the insulating filler members 14 in staggered order 60 and making a joint having a uniform and well balanced arrangement of parts throughout. However, it will, of course, be understood that I do not limit my invention to this precise construction and arrangement of 65 parts, since the improved combination splice

bar may be applied in other ways, in the construction of both standard and insulated joints, without departing from the spirit or principle of the invention.

In adapting the improvements to a joint 70 of the insulated type, of the form shown in the drawings, it is only necessary to supplement the insulation afforded through the filler members 14 by providing all of the bolts with suitable insulation, such for instance as the well known bushing and washer insulation designated by the reference number 16, and by employing base insulation plates 17 which are interposed between the rail bottoms and the base plates 8 and 12 respectively, and which insulation plates are 75 preferably formed at their outer edges with upturned insulating flanges 18 which are disposed at the outer edge of the rail base flanges and prevent metal contact with the 80 joint bars at these points. Insulation of a joint of this character is completed by an 85 insulating end post 19 placed between the rail ends.

In the manufacture of a splice bar constructed in accordance with the present invention, the same could be advantageously and economically made of cast steel or by 90 rolling and pressing operations, or in fact by any approved or practical method.

It is thought that the construction, operation, and many advantages of the herein-described process of making rail joints will be readily apparent with no other description, and it is also to be understood that 95 various changes in the form, proportion, and minor details of construction as fall within the scope of the appended claims may be resorted to without departing from the invention or sacrificing any of the advantages 100 thereof.

I claim:

1. A splice bar for rail joints having a rail supporting base section throughout and including a shoe angle member and a fishing 110 space member offset from said shoe angle member.

2. A splice bar for rail joints consisting of a fishing-space member, and a shoe angle member, each member extending one half 115 the length of the bar.

3. A splice bar for rail joints having a rail-supporting base section throughout its entire length and including a fishing-space member for one half of its length, and a 120 shoe angle member for the other half of its length.

4. A rail joint including the rails, a splice bar having a fishing-space member adapted to fit the fishing space of one rail end, and a shoe angle member receiving the other rail end, and a filler arranged within the shoe angle.

5. A rail joint including a splice-bar consisting of a rail base-supporting fishing- 130

space member fitting the fishing space of one rail end, and a shoe angle member receiving the other rail end, and a filler interposed between the latter and the upright of the shoe angle.

6. A rail joint including a splice bar consisting of a rail base-supporting fishing-space member fitting the fishing space of one rail end, and a shoe angle member receiving the other rail end, and a compressible filler interposed between the latter and the upright of the shoe angle.

7. An insulated rail joint including a splice bar having a fishing-space member fitting the fishing space of one rail end, and a shoe angle member receiving the other rail end, an insulating filler block interposed between the latter and the upright of the shoe angle, and insulation for the rail bases.

8. An insulated rail joint including a splice bar having a fishing-space member fitting the fishing space of one rail end, and

a shoe angle member receiving the other rail end, an insulating filler block interposed between the latter and the upright of the shoe angle, and insulation for the rail bases and the joint bolts.

9. An insulated rail joint including a splice bar consisting of a fishing-space member having a base plate and adapted to fit the fishing space of one rail end, and a shoe angle receiving the other rail end, a wooden filler block fitting the fishing space of the latter and against the inner side of the upright of the shoe angle, base insulation plates interposed between the rail bottoms and base plates of both members of the bar, bolt insulation, and an insulating end post.

In testimony whereof I hereunto affix my signature in the presence of two witnesses.

HOWARD L. WOOD.
